UNITED STATES PATENT OFFICE.

ANDERSON SONANDER, OF CHICAGO, ILLINOIS, ASSIGNOR OF ONE-HALF TO
JOHN A. HAGBERG, OF SAME PLACE.

SLIDING VISE.

SPECIFICATION forming part of Letters Patent No. 597,334, dated January 11, 1898.

Application filed December 16, 1896. Serial No. 616,841. (No model.)

To all whom it may concern:

Be it known that I, ANDERSON SONANDER, a citizen of the United States, residing at Chicago, in the county of Cook and State of Illinois, have invented certain new and useful Improvements in Sliding Vises; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in sliding vises of the class in which the movable jaw is moved by hand until it impinges on the article to be held, and then a toothed part is thrown into engagement with the screw-bolt, by which the clamping is effected; and the invention consists in the construction and novel combination of parts hereinafter described, pointed out in the appended claims, and illustrated in the accompanying drawings, in which—

Figure 1 is a longitudinal section of a vise provided with my improvement. Fig. 2 is a cross-section of Fig. 1, taken on the line 22, showing the device in normal position. Fig. 3 is a cross-section of the device, showing the screw-bolt released from engagement with the toothed parts; and Fig. 4 is a detail of an end view of Fig. 1. Fig. 5 is a detail of the cam-rod and sliding frame.

Similar numerals of reference refer to similar parts throughout the several views.

My invention consists in the construction of means whereby the screw-bolt is normally held between two toothed parts, one above and the other below, fixedly, so that the two toothed parts form substantially a nut in their mode of operation, thereby preventing the screw-bolt and the toothed parts from springing out of engagement partially or wholly and preserving the integrity of the threads. This I claim is a new result as well as new means therefor.

In the drawings, numeral 6 designates the fixed jaw of a vise of the class named; numeral 5, the movable jaw in which the screw-bolt 7 operates, connected with its sliding extension 8.

Numerals 9 designates the lower part of the fixed jaw 6 or frame of the vise. A fixed block 10 passes up through an opening in the frame 9 and is provided with an opening 55 through which the screw-bolt 7 passes freely. In my device I provide a space in this fixed block 10, in which I place a sliding frame 11 and adapt the parts so it has a vertical movement only in the block 10. This sliding frame, 60 preferably made with parallel sides and circular ends, as shown in the drawings, Figs. 2 and 3, is provided on its upper inner edge with teeth 12, adapted to engage the teeth of the screw-bolt 7, and on its lower end with a seat 65 13 for the cam 14 to rest on when the parts are in normal position. The purpose of this seat is to aid the spring 15 to hold the cam steadily in the position shown in Fig. 2. I also provide means for the engagement of the 70 cam 14 with the sliding frame 11, whereby the cam may be operated to raise it. Such means are preferably a projection 16, located near the lower part of the frame 11, so as to engage one end or edge of the cam 14, whereby 75 the frame 11 is raised a sufficient distance to lift the teeth 12 up out of engagement with the screw 7. Within this sliding frame 11 I place a toothed part 17 and adapt the parts to permit it to have a vertical movement. 80 This toothed part 17 is preferably of the form shown in the drawings, consisting of a half-nut having a projection against which the cam 14 operates, as shown in Fig. 2, and when it is released, as shown in Fig. 3, the toothed 85 part 17 drops out of engagement with the screw-bolt 7 by gravity. The cam 14 is a bar cam-shaped in cross-section, as shown in Figs. 2 and 3. It is provided with a circular extension 18, which passes through an end piece 19, 90 attached to the front end of the movable jaw, and a handle 20 for operating is attached, as shown. Around this circular extension 18 I place a coiled spring 15, one end of which is secured to the end piece 19 and the other 95 end is secured to the cam 14 and is adapted to hold the cam 14 in normal position, as shown in Fig. 2.

The mode of operation is as follows: The normal position of the device is to hold the 100 upper and lower toothed parts 12 and 17 in engagement with the screw-threads of the

screw-bolt 7, as shown in Fig. 2. In this position the movable jaw of the device can be moved only by the operation of the bolt. When the operator wishes to place an article in the vise, he presses the handle 20 down, thereby operating the cam to raise the teeth 12 and release the toothed part 17, whereby one is raised up and the other drops down out of engagement with the screw-bolt, leaving the bolt free to move in the block 10. He then manually moves the jaw 5, with its attached screw-bolt, in or out of the vise until the article can be easily placed in the vise. He then releases the handle, and the spring 15 turns the cam immediately back to the position shown in Fig. 2, thereby throwing the toothed parts again into engagement. The operator then turns the bolt a slight distance and clamps the article in place.

20 I am aware that sliding vises are in common use, and I do not therefore claim, broadly, a vise with a movable jaw with means to engage and release the screw-thread of the bolt; but

25 What I claim as new, and desire to secure by Letters Patent of the United States, is—

1. In a vise of the class named, the combination with the vise-screw of a sliding frame in the fixed part of the vise, its upper part provided with an upper half-nut, and also pro-

vided with a projection for lifting it and also 30 with a seat for the edge of a cam on its lower inner part adapted to form a catch to hold the cam in place when in vertical position: a lower half-nut sliding in said frame and provided with an extension for the impingement of a 35 cam: and an operating-rod passing through said sliding frame formed into a double cam in cross-section in that part thereof which slides through said frame and adapted to operate said half-nuts as described. 40

2. In a vise of the class named, the combination with the vise-screw of a sliding frame in the fixed part of the vise, its upper part provided with an upper half-nut and also with a projection for lifting it: a lower half-nut 45 sliding in said frame and provided with an extension for the impingement of a cam: and an operating-rod passing through said frame formed into a double cam in that part thereof which slides through the frame and adapted 50 to operate the half-nuts as described.

In testimony whereof I affix my signature in presence of two witnesses.

ANDERSON SONANDER.
